UNITED STATES PATENT OFFICE.

ISIDOR DEUTSCH, OF CINCINNATI, OHIO, ASSIGNOR TO WESTINGHOUSE ELECTRIC AND MANUFACTURING COMPANY, A CORPORATION OF PENNSYLVANIA.

CONTACT-FINGER AND BASE.

1,315,950.

Specification of Letters Patent. Patented Sept. 16, 1919.

Application filed February 21, 1914, Serial No. 820,217. Renewed February 13, 1918. Serial No. 216,942.

To all whom it may concern:

Be it known that I, ISIDOR DEUTSCH, a citizen of the United States, and a resident of Cincinnati, in the county of Hamilton and State of Ohio, have invented a new and useful Improvement in Contact-Fingers and Bases, of which the following is a specification.

My invention relates to contact fingers and bases therefor which are adapted for use in connection with controllers of the drum type and similar circuit-controlling mechanisms.

My invention has for its object to provide a means whereby the contact fingers and related parts of controlling mechanisms may be protected from damage that may be caused by abnormal stresses upon the same.

A contact finger, as commonly constructed, comprises a contact element which is mounted upon the free end of a blade spring, the other end of the spring being fixed to a relatively stationary part. It may occur in the operation of control mechanism, that the engaging surfaces of the contact segments or of the contact fingers may become roughened or pitted as a result of arcs which follow the opening and closing of the controlled circuits. Under these conditions, movement of the segments or of the contact fingers may cause the parts to firmly engage. When the relative movement of the controller drum is toward the point of support of the contact finger, the result has been, ordinarily, to cause the supporting spring to buckle until the parts become disengaged. The spring, if not broken, may be permanently distorted so that the contact finger will not engage the coacting contact segments with the proper pressure or at the proper point in the relative angular movement of these parts. As is well known, it is highly desirable in the interest of safe operation, that each part of a controller should perform its proper function at all times.

In carrying out my invention, I employ a base member which supports the contact finger and which is provided with means for taking up the thrust upon the contact finger should the latter be caught by the roughened surface of the contact segments as above described. By means of this arrangement, I effectually prevent injury to

the supporting spring and thus avoid the 55 delay and expense incident to the repair or replacement of the damaged parts.

In the accompanying drawing, the single figure is a side view, in elevation, of a base and contact finger, the supporting member 60 being shown in section.

A base member 1, of irregular shape, is provided with a rectangular opening 2 to receive a supporting arm 3. The base member 1 is provided with a slit 4 to provide 65 a means for clamping the base member to the arm 3 by means of a clamping screw 5. A second slit 6 and a clamping screw 7 provide a means for rigidly clamping a pair of springs 8 and 9, of phosphor bronze or 70 similar material. The spring 9 is provided with an intermediate curved portion 10 to render the springs more rigid at this point. A contact finger 11 is attached to the free end of the spring 8 by means of a 75 bolt 12. A lug 13, which is integral with the base member 1, is provided with an opening 14 in which the bolt 12 may reciprocate to act as a guide for and to limit the movement of the contact finger 11. 80

The base member 1 is provided with a shoulder 15 which is normally separated by a small space from the end 16 of the contact finger 11. Should the controller drum 17, a portion of which is indicated by 85 dot and dash lines, be moved in the direction of the arrow and the finger 11 be engaged by a roughened surface on the drum to carry the finger in the same direction, the end portion 16 of the finger will engage the 90 shoulder 15 after a slight endwise movement. The springs 8 and 9 will, therefore, be bent only slightly, the thrust being substantially entirely taken up by the shoulder 15. The curved portion 10 of the spring 95 9 prevents the springs 8 and 9 from being broken or distorted by distributing the stress tending to bend the springs at their middle point. The only damage that can result, under the circumstances above described, is to bend the finger 11, and that only in the infrequent instances in which the engaging parts do not move relatively after a considerable thrust has been applied to the contact finger. When the drum rotates in a direction opposite to the arrow, 100 no damage can result to the contact finger and its related parts as the force is applied

to the finger in a direction away from the point of support of the springs 8 and 9 and at an angle to a line passing therethrough, thus permitting the finger to move 5 laterally to be disengaged from the drum.

I claim as my invention:

1. The combination with a base member having a shoulder portion, of a contact element resiliently supported by said base member and having a portion adjacent said shoulder portion to coact therewith, and means for guiding relative movements of the base member and the contact element. 10
2. The combination with a base member having an integral shoulder portion, of a contact element having a portion to engage said shoulder portion at the end of a predetermined movement thereof, a supporting spring mounted on said base member, and a unitary means for clamping said contact element to its supporting spring and for guiding the movements thereof. 15
3. The combination with a base member, a contact element, and a resilient supporting means secured to the base member, of a single means for clamping the contact element to its supporting means and for limiting the movements of the contact element. 20
4. The combination with a base member, of a blade spring attached at one end to said base member and provided with an intermediate curved portion, a contact element, means for clamping said contact element to the blade spring, said means also serving to limit and guide the relative movements of the contact element and the base member, and means integral with said base member for engaging the contact element at the end of a predetermined relative movement. 25
5. The combination with a base member having a projection, of a contact element resiliently supported by said base member and having a portion adjacent said projection for engagement therewith at the end of a predetermined relative movement, and means for limiting and guiding the relative movements of the several parts. 30
6. The combination with a base member having a stop portion, a contact element, and a support therefor, said contact element being resiliently held in operative position, of a single means for clamping said contact element to its support and for engaging said 35
7. The combination with a base member having an opening, a blade spring secured to said base member, and a contact element carried by said spring, of a bolt located in said opening, said bolt alone clamping said contact element to said spring, the head of said bolt engaging said base member to limit the forward movement of said contact element. 40
8. The combination with a base member having a shoulder portion which is immovable with respect to said base member, of a contact element resiliently supported by said base member and having a portion adapted to engage said shoulder portion at the end of a predetermined relative movement. 45
9. The combination with a base member having a shoulder portion at one end, of a pair of blade springs attached at the other end and extending toward said one end, the blade spring which is farthest removed from said shoulder portion being provided with an intermediate curved portion, and a contact element secured to said blade springs at their free ends and having a portion for co- 50 operating with said shoulder portion. 55
10. In a controller, a support, a resilient member carried thereby, a contact finger secured to said member, a stop secured to said support for limiting the degree of movement of said finger in one direction, and means for limiting the degree of movement of said finger in the opposite direction. 60
11. In a controller, the combination with a support, a resilient member secured thereto and a contact finger mounted on said resilient member, of a stop member secured to said support and provided with an opening, a bolt located in said opening, the head of said bolt engaging said stop to limit the degree of movement of said finger, and means for locking said bolt in adjusted position. 65

In testimony whereof, I have hereunto subscribed my name this 14th day of February, 1914.

ISIDOR DEUTSCH.
